W. R. D'ALFONSO

TONE MODIFIER FOR WIND INSTRUMENTS

Filed Aug. 1, 1921

FIG. 1

FIG. 2

INVENTOR

W. R. D'Alfonso

UNITED STATES PATENT OFFICE.

WILLIAM ROMEO D'ALFONSO, OF OAKLAND, CALIFORNIA, ASSIGNOR TO UNIVERSAL TELESCOPE MUTE COMPANY, OF SAN FRANCISCO, CALIFORNIA, A CORPORATION OF CALIFORNIA.

TONE MODIFIER FOR WIND INSTRUMENTS.

Application filed August 1, 1921. Serial No. 489,144.

To all whom it may concern:

Be it known that I, WILLIAM R. D'ALFONSO, a citizen of the United States, residing at 6018 Colby St., Oakland, Alameda County, State of California, have invented a new and useful Tone Modifier for Wind Instruments Commonly Classified as of the Brass Family, of which the following is a specification.

10 This invention relates to improvements in mutes for cornets or any of the brass musical instrument family, and consists of the provision of a device of such character as can be easily and quickly adjusted through novel 15 means so as to effect the raising and the lowering of the tone.

The main object of this present invention is to provide means whereby the tone or pitch of a note played on any cornet or 20 brass instrument, with the mute in place, can be modified and brought into perfect accord or pitch with the same note or tone played or produced on said cornet or member of the brass instrument family including 25 cornet, trumpet, alto, Flügel horn, trombone, baritone, tuba, French-horn, ballad-horn, etc., when used open or without mute; which result can be obtained by the use of my improved mute.

30 In the accompanying drawing, Figure 1 is a front elevation of my improved mute set in place, within the mouth of a cornet (shown in section) with its head at the highest limit. Figure 2 is a view at right angles to Fig. 1 showing the mute in vertical section and at its lowest limit.

Referring to the drawing, 1 designates the mute generally which consists of a frusto-conical tube 2 provided with the usual cork 40 spacers 17 to hold it firmly inside the bell of cornet A. Its upper end 3 is cylindrical and threaded as at 4 to receive the threaded end of a cylindrical tube 5 which near its lower end is slotted as at 6 in order to leave 45 room, for a pinion to be described presently;

in front of said slot, sufficiently wide to cover it up and secured to the tube 5 by screws 8, is a bearing 7 through which passes a shaft 9 carrying at one end a milled disk 10 conveniently placed between the center 50 and the edge of the bell of cornet A so that it may be rotated at will by the player.

On said shaft 9 and within a chamber 11 provided in the bearing 7 is secured a small pinion 12, meshing with a rack 13 fastened 55 by screws 14 to a tube 15 telescoping within the stationary tube 5.

This tube 15 at its upper end supports an enlarged bell or head 16 it being welded or riveted to it, or if desired, made integral 60 with it.

The tube 15 is made of such length as to come near the inner wall of tube 2, without touching it when brought to its lowest point; it is also provided with a longitudinal slot 65 18 of about the same dimensions as those of rack 13 thus allowing the teeth of said rack to protrude through it and come into mesh with pinion 12.

The operation of the mechanism is as 70 follows:—By turning the disk 10 in one direction, tube 15 and head 16 will be raised, while by turning it in the opposite direction tube and head will be lowered; the amount of the turning depending upon the degree 75 of pitch or difference in tonality detected by the ear of the player.

Having thus described the invention, what is claimed as new is,

1. A mute comprising hollow telescopic sections one of which is open at both ends and the other of which is open at one end and closed at the other and means for moving one of said sections relative to the other to increase or decrease the volume within the sections, which means comprises a shaft 80 mounted for rotation on one of said sections, a pinion on said shaft, a rack bar on the other section with which the pinion engages 85 and a handle portion on said shaft. 90

2. A mute comprising a hollow frusto-conical member adapted to fit into the mouth of a horn, a tubular portion carried by the outer end of said member, said tubular portion being enlarged and externally screw threaded, said frusto-conical member having internal screw threads for cooperation with the screw threads on the tubular portion, another tubular portion telescoping the 10 first named tubular portion and means for

sliding said last named portion inwardly or outwardly, said sliding tubular portion adapted to extend into and out of said frusto-conical member.

In testimony whereof, I hereunto affix my 15 signature in the presence of two witnesses.

WILLIAM ROME O D'ALFONSO.

Witnesses:

JOHN R. TYRRELL,
FRANK ROSSI.
